STEAM GENERATOR

Frederick Wightman, Los Angeles, Calif., assignor
to Walter B. Kerrick, Los Angeles, Calif.

Application August 28, 1939, Serial No. 292,259

11 Claims. (Cl. 122—448)

This invention relates generally to heat exchange apparatus, and more particularly to steam generators.

An object of the invention is to provide a steam generator which is structurally characterized by means insuring a supply of dry steam under any and all operating loads up to the relatively large steaming capacity of the generator, and in a manner to positively prevent the carrying over of water into the steam delivery line, all automatically and economically with respect to the consumption of fuel.

Another object of the invention is to provide a steam generator of the above described character which embodies an ebullition chamber and primary and secondary generating coils associated therewith and with the combustion chamber of the generator in such manner as to enable the supply of fuel and water to be accurately controlled automatically in accordance with the demand for steam which will be supplied in a dry state irrespective of the demand.

With these and other objects in view, the invention resides in the combinations, arrangements and functional relationships of elements as set forth in the following specification and particularly pointed out in the appended claims.

In the accompanying drawing the figure is a semi-diagrammatic view showing in vertical section one form of steam generator embodying the invention.

Referring specifically to the drawing, the invention comprises a suitably insulated furnace 10 defining a combustion chamber 11. At the top of the front wall of the furnace is a fuel burner 12 which is illustrated as being of the type to burn a gaseous fuel delivered thereto from a suitable source of pressure supply through a pipe 13 having a valve 14 adapted to be controlled automatically, as will be later described.

Suitably supported above the furnace 10 is a steam and water separator 15 in the form of a horizontally elongated metal shell adapted to safely withstand the maximum steam pressure 45 to be generated.

The separator 15 is divided by a dam or partition 16 into an ebullition space 17 and a control space 18, the bottom of the separator in the ebullition space inclining downwardly from the dam. A steam generating coil 19 is supported in the combustion chamber 11 and is connected by a pipe 20 to a reservoir 21 in which water is maintained at a predetermined level by a float-operated valve 22 which controls the delivery of 50

water to the reservoir from a pipe 23 connected to a source of water supply under pressure.

By means of a pipe 24 the other end of the coil 19 is connected to the separator 15, the pipe 24 entering the top of the separator and extending downwardly therein at its lowermost end to a point below the minimum water level in the ebullition space 17. A suitable gage glass 25 is provided to indicate the water level in the space 17, and a pressure gage 26 is supported on the separator to indicate steam pressure therein.

A steam generating coil 27 is supported in the combustion chamber 11 above the coil 19 so as to be disposed in the hottest zone of flame from the burner 12, a suitable flame spreader 28 being interposed between the burner and the coil 27. Thus, the flame from the burner in traveling downwardly in the combustion chamber, as indicated by the broken line arrows, first passes the coil 27 and then the coil 19, the residual gases discharging through a suitable flue 29 connected to the furnace at the bottom of the chamber 11.

The top horizontal branch 30 of the coil 27 is connected by a vertical pipe 31 to the separator 15 at the bottom of the control space 18, and a baffle 32 is interposed between the inlet provided by the pipe 31 and the steam outlet 33 connected to the top of the separator so as to communicate with the steam space 34 therein.

30 The lowermost branch of the coil 27 is connected by a vertical pipe 35 to the separator 15 at the lowermost end of the ebullition space 17 by an intervening enlarged section 36 which provides a water outlet from the separator. It will be noted that the pipe section 36 and the depending end of the pipe 24 from the generating coil 19 are co-axially related to co-act in forming an ejector which functions in a manner to be later described.

35 40 The aforementioned horizontal branch 30 of the coil 27 is constructed of brass or other metal having a high co-efficient of expansion and constitutes a thermostat. At one end of the branch 30 is an extension 38 which seats against an adjusting screw 39, and at the other end of said branch is a rod 40 which engages the stem of the valve 14 to force the latter towards its closed position against the urging action of a spring 42, to open the valve.

45 50 A piston type force pump 43 is connected in circuit with the water pipe 20 and is driven by an electric motor 44 connected by conductors 45 and 46 to a source of current supply. The supply of current to the motor 44 is controlled by a manual switch 46 and a normally closed thermo-

responsive switch 48 applied to a water pipe 49 leading from the bottom of the separator 15 in its control section 18 to the reservoir 21, and provided with a steam trap 50.

The operation of the invention is as follows:

The manual switch 47 is first closed to start the motor 44 and operate the pump 43 so that water will be supplied through the pipe 20, primary coil 19 and pipe 24 to the ebullition space 17 to a level below the top of the dam 16, as can be determined by observing the gage glass 25. The pump is now shut down by opening the manual switch 47.

The burner 12 is now lighted to heat the coils 19 and 27, the heat applied to the secondary coil 27 causing thermo-circulation to be effected therein in the direction of the full line arrows, it being noted that the water level in the ebullition space is higher than at the inlet of the pipe 31 to the bottom of the control space 18 so that uni-directional circulation in accordance with the arrows will be induced.

As heat from the burner is also being applied to the coil 19, the thermo-circulation will be accelerated by the discharge end of the pipe 24 and the pipe section 36 acting as an ejector.

By the combined natural and artificially accelerated thermo-circulation, the temperature of the body of water in the ebullition space is increased to raise the steam pressure in the separator 15 to a predetermined amount in accordance with the adjustment of the thermostat control screw 39, to cause the thermostatic pipe branch 30 to so actuate the fuel valve 14 that the flow of fuel to the burner will provide the requisite amount of heat to maintain a predetermined steam pressure in the separator.

The manual switch 47 is again closed so as to place the pump 43 under the automatic control of the thermo-responsive switch 48.

Any excess water in the ebullition space 17 flowing over the dam 16 or rising in the pipe 31 into the control space 18 is free to flow through the pipe 49 past the steam trap 50 and to discharge into the reservoir 21, the heat of this water re-acting upon the thermo-responsive switch 48 to open same and thus stop the motor 44.

So long as there is sufficient demand for steam to evaporate the water in the ebullition space 17 as fast as the pump 43 supplies water thereto, the pump will continue in operation. Thus, it will be clear that according as the demand for steam increases or decreases, the pump will be started or stopped to maintain the pre-determined water level in the ebullition chamber.

As the demand for steam varies, the pressure is varied in the ebullition and control spaces and in the thermo-expansive tube 30 connected in series with the secondary coil 27. Should there be a rise or fall in steam pressure, the temperature will rise or fall accordingly. Thus, under the action of the thermo-expansive tube 30, more or less fuel will be supplied to the burner 12 according as the demand for steam increases or decreases.

The varying supply of fuel to the burner acts on the liquid in the primary coil 19 by heating the liquid to increase its volume and velocity to a greater or lesser extent. Steam particles forming in the liquid at high temperatures drive the water particles from the discharge end of the coil 19 with more or less force so as to accordingly accelerate the circulation in the coil 27 which latter is in the hottest zone of the

generator. Thus the amount of steam generated in the secondary coil 27 will be increased or decreased to aid in maintaining a substantially constant pressure in the separator 15.

5 What is claimed is:

1. A steam generator comprising: a steam generating chamber having an ebullition space and a control space into which water in the ebullition space can flow when reaching a predetermined level; a heating coil having an inlet for said chamber communicating with the control space at a lower level than a normal water level in the ebullition space, and an outlet for said chamber communicating with the ebullition space at a location to be submerged by water therein, whereby when said coil is heated, thermal circulation through the coil will be effected from said outlet to said inlet; means for supplying water to the ebullition space and including means co-actable with said outlet to accelerate the aforesaid thermal circulation; means co-actable with said control space and water supply means to maintain a supply of water in the ebullition space irrespective of the demand for steam from said chamber; and means for heating said coil to maintain a predetermined steam pressure in said chamber.

2. A steam generator comprising: a steam generating chamber having an ebullition space and a control space into which water in the ebullition space can flow when reaching a predetermined level; a heating coil having an inlet for said chamber communicating with the control space at a lower level than a normal water level in the ebullition space, and an outlet for said chamber communicating with the ebullition space at a location to be submerged by water therein, whereby when said coil is heated, thermal circulation through the coil will be effected from said outlet to said inlet; means for supplying water to the ebullition space and including means co-actable with said outlet to accelerate the aforesaid thermal circulation; means responsive to water entering the control space from said inlet and/or the ebullition space to control said water supply means by preventing the delivery of an excess of water to the ebullition space; and means for heating said coil to maintain a predetermined steam pressure in said chamber.

3. A steam generator comprising: a steam generating chamber having an ebullition space and a control space into which water in the ebullition space can flow when reaching a predetermined level; a heating coil having an inlet for said chamber communicating with the control space at a lower level than a normal water level in the ebullition space, and an outlet for said chamber communicating with the ebullition space at a location to be submerged by water therein, whereby when said coil is heated, thermal circulation through the coil will be effected from said outlet to said inlet; a second heating coil having an inlet adapted for connection to a source of water supply, and an outlet communicating with said chamber and co-actable with the aforesaid outlet of the latter to accelerate the thermal circulation by the action of water delivered under pressure to the chamber; means responsive to water entering the control space from its inlet and/or the ebullition space to control the supply of water under pressure to the second said coil so as to prevent an excess of water being delivered to the ebullition space; and means for heating said

coils to maintain a predetermined steam pressure in said chamber.

4. A steam generator comprising: a steam generating chamber having an ebullition space and a control space into which water in the ebullition space can flow when reaching a predetermined level; a heating coil having an inlet for said chamber communicating with the control space at a lower level than a normal water level in the ebullition space, and an outlet for 10 said chamber communicating with the ebullition space at a location to be submerged by water therein, whereby when said coil is heated, thermal circulation through the coil will be effected from said outlet to said inlet; a second 15 heating coil having an inlet adapted for connection to a source of water supply, and an outlet communicating with said chamber and co-actable with the aforesated outlet of the latter to accelerate the thermal circulation by the action of water delivered under pressure to the chamber; a pump delivering water under pressure to the second said coil; a motor driving the pump; a circuit including a source of current supply, said motor and a switch; and means co-actable with said switch and responsive to the heat of water entering said control space from its inlet and/or the ebullition space to so control the motor as to prevent an excess of water from being delivered to the ebullition space by the pump; means including a burner for heating said coils; and thermo-responsive means controlling the supply of fuel to the burner to maintain a predetermined steam pressure in said chamber.

5. A steam generator comprising: a furnace having a combustion chamber; means for generating heat in the combustion chamber; heating coils in the combustion chamber; a separator having a steam outlet; means connecting the inlet and outlet of one of said coils to the separator at locations to effect uni-directional thermal circulation through said one of the coils when heated; means connecting the inlet of the other of said coils to a source of water supply, and the outlet to said separator at a location to cause thermal circulation in said one of the coils to be accelerated by the discharge of fluid under pressure into the separator from the other of said coils; thermo-responsive means operatively associated with the combustion chamber to control the supply of fuel to said heat generating means to maintain steam pressure in the separator; and means controlling the supply of water to the separator from said other coil by preventing the delivery of an excess amount of water to the separator.

6. A steam generator comprising: a furnace having a combustion chamber; means for generating heat in the combustion chamber; heating coils in the combustion chamber; a separator having a steam outlet; means connecting the inlet and outlet of one of said coils to the separator at locations to effect uni-directional thermal circulation through said one of the coils when heated; means connecting the inlet of the other of said coils to a source of water supply, and the outlet to said separator at a location to co-act with the inlet of said one of the coils in defining an ejector accelerating the aforesated thermal circulation by the discharge of fluid under pressure from the other of said coils; means controlling the supply of fuel to the heat generating means to maintain steam pressure in the separator; and means controlling the supply

of water to the separator from said other coil by preventing the delivery of an excess amount of water to the separator.

7. A steam generator comprising: a furnace having a combustion chamber; means for generating heat in the combustion chamber; heating coils in the combustion chamber; a separator having a steam outlet; means connecting the inlet and outlet of one of said coils to the separator at locations to effect uni-directional thermal circulation through said one of the coils when heated; means connecting the inlet of the other of said coils to a source of water supply, and the outlet to said separator at a location to cause thermal circulation in said one of the coils to be accelerated by the discharge of fluid under pressure into the separator from the other of said coils; thermo-responsive means operatively associated with the combustion chamber to control the supply of fuel to said heat generating means to maintain steam pressure in the separator; a pump delivering water under pressure to said other coil; an electric motor driving the pump; an electric circuit including a source of current supply, the motor and a thermo-responsive switch for opening the circuit; and means by which an excess of water in the separator will open said switch so as to automatically maintain a supply of water in the separator.

8. A steam generator comprising a plurality of heating coils; heating means for said coils; means defining an ebullition chamber having a steam outlet; means connecting one of said coils in circuit with said chamber to effect thermal circulation therethrough upon heating of the coil; means for supplying water under pressure to the other of said coils; means connecting said other coil to the ebullition chamber at a location to accelerate the aforesaid thermal circulation under the action of water discharging from said other coil; means controlling said heating means to maintain steam pressure in the ebullition chamber; and means controlling the water supplying means to maintain a supply of water in said chamber irrespective of the demand for steam.

9. A steam generator comprising: a steam generating chamber having an ebullition space and a control space into which water in the ebullition space can flow when reaching a predetermined level; a heating coil in a liquid circuit with the ebullition and control spaces, to effect thermo-circulation through the coil from the ebullition space to the control space; means for supplying water to the ebullition space and including means co-actable with said coil to accelerate the aforesated thermal circulation; means co-actable with said control space and water supply means to maintain a supply of water in the ebullition space; and means for heating said coil to generate steam in the ebullition space.

10. A steam generator comprising: a steam generating chamber having an ebullition space and a control space into which water in the ebullition space can flow when reaching a predetermined level; a heating coil in a liquid circuit with the ebullition and control spaces, to effect thermo-circulation through the coil from the ebullition space to the control space; a second heating coil adapted for connection to a source of water supply and co-acting with the first coil to accelerate the aforesated thermal circulation as water is supplied by the second coil to the ebullition space; means co-actable

with said control space and second coil to maintain a supply of water in the ebullition space; and means for heating said coils to generate steam in the ebullition space.

11. A steam generator comprising: a thermo-circulatory coil; an accelerating coil; a source of heat for the coils supplying more heat to the thermo-circulatory coil; means defining an ebullition chamber having a steam outlet and its water level above the level of the thermo-circulatory coil; means connecting the thermo-circulatory coil in circuit with said chamber at points below the water level therein to effect

5 thermal circulation therethrough upon heating of the coil; means for supplying water under pressure to one end of the accelerating coil; and means through which fluid is conducted from the other end of the accelerating coil to the ebullition chamber and downwardly to a point therein, from which the fluid will, by its velocity and weight, discharge into an end of the thermo-circulatory coil so as to act to accelerate the 10 aforementioned thermal circulation through the thermo-circulatory coil.

FREDERICK WIGHTMAN.
